E. P. FARUM,

LOCK FOR SLIDABLE WINDOWS,
APPLICATION FILED MAY 28, 1920.

1,420,993.

Patented June 27, 1922.

UNITED STATES PATENT OFFICE.

ELECIE P. FARUM, OF OAKLAND, CALIFORNIA, ASSIGNOR TO DON LEE, OF SAN FRANCISCO, CALIFORNIA.

LOCK FOR SLIDABLE WINDOWS.

1,420,993.

Specification of Letters Patent. Patented June 27, 1922.

Application filed May 28, 1920. Serial No. 385,040.

To all whom it may concern:

Be it known that I, ELECIE P. FARUM, a citizen of the United States, and a resident of Oakland, county of Alameda, and State of California, have invented a new and useful 5 Lock for Slidable Windows, of which the following is a specification.

My invention relates to a lock or clamp for preventing the rattle or movement of 10 slidable windows, especially of the class which are adapted for use in connection with the sides of the enclosed type of body of an automobile.

An object of the invention is to provide a 15 lock for slidable windows of the character described which can be constructed and assembled for the most part directly on the sash before the latter is positioned in the window frame, thus obviating to a great extent the necessity of working under the difficult conditions such as obtain when the 20 most of the construction and assembling must be done in the pockets of the top and body of the automobile.

Another object of the invention is to provide a lock for a slidable window which will automatically lock or clamp the window sash as it reaches the limit of its movement in 25 one direction, and which will be automatically disengaged or released upon the initiation of the returning movement of the sash.

The invention possesses other objects and features of advantage, some of which, with the foregoing, will be set forth in the following description of the preferred form of 35 my invention which is illustrated in the drawings accompanying and forming part of the specification. It is to be understood that I do not limit myself to the showing made by the said drawings and description, 40 as I may adopt variations of the preferred form within the scope of my invention as set forth in the claims.

Referring to said drawings:

45 Fig. 1, is a side elevation of the upper portion of an "enclosed car" provided with the sliding windows and lock of my invention, parts of the structure being broken away to disclose the ordinarily hidden portions more clearly.

Fig. 2, is a transverse vertical section of one side of the body, the plane of section being indicated by the line 2—2 of Fig. 1.

Fig. 3, is a horizontal section of one side

of the body as seen when looking upwardly 55 from just below the track.

Briefly expressed my invention cooperates with a set of window sashes arranged in a suitable frame between the forward and rear end of the body top and between the 60 upper and lower edge thereof. Means are provided, which include a pivoted bar and a stop, for locking a sash against movement as it reaches the extent of its movement in one direction. Upon initiating the return 65 movement of the sash a second stop is encountered which acts to release the sash from its locked position so that it may be moved freely. Means are included for adjusting the degree of tension tending to retain the 70 sash in its locked position.

A detailed description of my invention follows:

The body 2, of the automobile, in which my apparatus is embodied, is provided in 75 one or more of its sides with an opening 3, which extends downwardly from the lower edge of the top 4, to the upper edge of the doors 5, and between the permanent window 6, and the windshield 7. The sides of the 80 opening are provided with what may be termed, a frame 8, which comprises walls 9 and pockets 11 and 12, in which are slidably disposed a set of window sashes 13 and 14.

The pocket 11 is formed inside of the permanent window 6 and serves to enclose the 85

slidable sashes 13 and 14 when they are in their rearward or open position. The pocket 12 is formed in the lower edge of the

top and extends longitudinally for practically the full length of the top. Fixed in 90 the pocket 12 and spaced from the side walls 9 thereof is a track member 16 provided on

its opposed sides with grooves 17 and 18 in which engage hangers 19 and 21 respectively 95

and from which depend the sashes 13 and 14 respectively. The sash 13, when in its forward or closed position, is arranged to engage 100

the forward end of the opening 3 and is prevented from swinging outward by means of a suitable guide 22 formed on the top of the doors. The sash 14 when in its

forward position is adapted to engage the space between the permanent window 6 and the sash 13 when the latter is extended. The 105

sash 14 is prevented from being swung transversely by means of the guide 23 also pref- 110

erably formed on the door. As shown in

the drawing the sash 13 is held in its closed position by the hanger 19 and the sash 14 is held in its closed position by the hanger 21.

Fig. 1 suitable handles 24 and 26 may be provided on the sashes for readily sliding them longitudinally in the frame.

Means are provided for locking or clamping the sashes against movement when they assume their forward or closed position. Arranged in the pocket 12 and between the top of the sashes and the bottom of the track member are longitudinally disposed bars 27 and 28. The bars are connected by sets of parallel links 29 and 31 to the sashes 13 and 14 respectively. When a sash is not quite in its extreme forward position the links and bar with which it is associated assume the collapsed position shown in connection with the intermediate sash 14 in Fig. 1 of the drawings; however, when the sash approaches its forward position, the bar strikes against one of the abutments 32 and 33 which are in the path of the bars 27 and 28 respectively whereby the bar is forced upwardly into tight engagement with some part of the frame, such as the bottom of the track member upon the continuation of a slight forward movement and thereby practically arresting further movement of the sash, and preventing any rattle.

Means are provided for varying the amount of tension that will obtain between the bar and track for a given movement of the sash preparatory to being locked. Extending preferably from the bottom of the track member and adapted to overlie the central portion of the sashes when the latter are in their forward positions, are screws 34 and 36 disposed in the vertical plane of the sashes 13 and 14 respectively. In order to vary the said tension it is merely necessary to screw the bolt inwardly or outwardly, inward movement of screw serving to relieve the tension, whereas outward movement will increase the tension.

Means are also provided for causing the locking mechanism to be automatically released or collapsed upon initiating the return movement of the sash. Fixed to the track and aligned with the bars are stops 37 and 38 which lie just back of the bars when the sashes are in their extreme forward position. The stops 37 and 38 are much shorter than the stops 27 and 28 so that the bars clear the former during the forward movement of the sashes or in other words, while the bars are collapsed; however, when the bars are extended as shown in connection with sash 13 of Fig. 1, the stops 37 and 38 will lie directly in the path of the bar with which it is aligned, thereby causing the bar to move downwardly as soon as the returning movement of the particular sash is commenced.

It will be noted that when the bar is moved from its collapsed position to its extended position, the pivotal point 41 between the link and the bar moves from one side to the opposite side of a vertical line

which would intersect the pivotal point 42 of the link and sash, and therefore means are provided for limiting the extendible movement of said links after the point 41 has passed a short distance beyond said line, 70 so that the bars may be prevented from collapsing and thereby inadvertently releasing the sash. Projecting preferably from the bottom of the track and engaging inclined recesses 43 and 44 of the sashes 13 and 14 75 respectively are adjustable pins 45 and 46. When the bars are in their extended position the pins preferably engage the shallow portion of the recess and when the bar is collapsed the pins are adapted to rest in the deep portion of the recess.

I claim:

1. In combination with the side window frame of the enclosed type of body of an automobile, a horizontally disposed track at 85 the top portion of said frame, a window sash slidably disposed in said frame, a hanger engaging said track and secured to said sash, a vertically movable bar arranged between the track and the top of said sash, a 90 pair of horizontally aligned longitudinally spaced parallel links of equal length connecting said bar to said sash, an abutment fixed to said track arranged to throw the bar into tight engagement with the track 95 as the sash approaches the limit of its movement in one direction, and a second abutment fixed to said track and engageable by said bar and link mechanism at the initiation of the return movement of said sash 100 for releasing said engagement of the bar and track.

2. In combination with the side window frame of the enclosed type of body of an automobile, a horizontally disposed track at 105 the top portion of said frame, window sashes slidably disposed in said frame, hangers supported in said tracks and secured to said sashes, a separate transversely movable bar arranged between each sash and the track, 110 a pair of substantially horizontally aligned longitudinally spaced links connecting the bars to the sashes, abutments fixed to the track and arranged to throw said bars outwardly in extended position and in tight 115 engagement with the track as the respective sash approaches the limit of its movement in one direction, a second set of abutments fixed to said track and adapted to be engaged by said bar and link mechanism at 120 the beginning of the return movement of said sash for releasing the engagement of said bar and track, and means for limiting movement of the bar in its extended and collapsed positions.

3. In combination with the side window frame of the enclosed type of body of an automobile, a horizontally disposed track at the top portion of said frame, a window sash slidably disposed in said frame, a hanger en- 130

gaging and supported by said track and secured to said sash, a transversely movable bar arranged between said sash and track, horizontally aligned longitudinally spaced 5 parallel links of equal length connecting said bar to said sash, an abutment arranged to throw the bar in engagement with said track whereby the pivotal point of the link and itself will move from one side to the 10 opposite side of a vertical line intersecting the pivotal point of the link and the sash as the latter approaches the limit of its movement in one direction, a second abutment fixed to said track and engageable by 15 said bar and link mechanism at the beginning of the return movement of said sash for moving the pivotal point of the bar and link back again, means for limiting the movement of the bar in both positions, and 20 means for varying the tension between the bar and track in their engaged position.

4. In combination with a window frame,

a track fixed therein, a sash slidable in said frame, a hanger engaging said track and supporting said sash, a friction bar interposed between said track and sash, links connecting said bar and sash together, an abutment on said track adapted to engage and throw said bar into engagement with said track as said sash approaches a closed position, and a second abutment fixed on said track arranged to remain disengaged during the closing movement of said sash and adapted to engage and throw said bar out of engagement with said track at the initiation of 30 the return movement of said sash.

In testimony whereof, I have hereunto set my hand at Oakland, California, this 24th day of May, 1920.

ELECIE P. FARUM

In presence of—
GERTRUDE L. RAND,
L. L. M. SALSBURY.
